BAFFLE TYPE MUFFLER WITH PLURAL TUBULAR PASSAGES

Frank Christiano and Nicholas Christiano,
Hartford, Conn.

Application January 26, 1948, Serial No. 4,358

3 Claims. (Cl. 181—50)

1

This invention relates to baffle type muffler with plural tubular passages and more particularly to mufflers such as intended for internal combustion engines.

An object of the invention is to provide a muffler which is highly efficient in its operation, inexpensive to produce, and which may be used at the end of an exhaust pipe.

A further object of the invention is to provide such a muffler which is compact and attractive in appearance.

Further objects and advantages of this invention will be more clearly understood from the following description and from the accompanying drawings, in which—

Fig. 1 is an end view of a muffler embodying our invention.

Fig. 2 is a side view thereof.

Fig. 3 is a side view in central vertical section.

In the embodiment shown, our invention embodies a muffler having a casing or outer shell 5 with an end plate 6 at one end thereof that is provided with an opening which communicates with the interior of a tubular portion 7 that receives the end of an exhaust pipe 8 and has a plurality of slits 9 permitting the said tubular portion to be secured to said exhaust pipe by means of a suitable clamp 10. At the interior of said casing there is provided a screen 11 at one end which extends across the opening in the plate 6 and a screen 12 at the opposite end which is supported by the ends of a plurality of tubular sections 13, 14 and 15.

The section 13 is preferably smaller than the sections 14—15 in order to provide a preferred formation whereby the open end of the muffler casing is flattened, as illustrated in Fig. 1, and the said tubes are joined together and secured to the casing by spot welding, or the like, as indicated at 16, to retain the said tubes in position wherein they are in alignment with the end of the casing 5 and support the screen 12.

The inside of the casing between the screens 11 and 12 is filled with a suitable material 17, such as a wool made of glass fibers or the like, to provide a muffling effect for the exhaust gases passing through said muffler. This wool has been found highly efficient in reducing the noises of combustion with a minimum of back pressure. In fact, said wool material has been found to be far more effective and with less back pressure than the conventional form of baffle plates usually provided in mufflers.

We claim:

1. A muffler of the character described comprising a casing, an end plate having an opening therein and a tubular portion, a perforate sheet

2

of material contained within said casing and positioned against said end plate across said opening, a plurality of tubular members within and adjacent the opposite end of said casing and extending longitudinally thereof, a perforate sheet of material within said casing and against the ends of said tubular members, and a fibrous mass filling said casing between said perforate sheets.

2. A muffler of the character described comprising a casing, an end plate having a tubular member extending therefrom and communicating with an opening in said end plate, a disk of wire mesh material contained within said casing and resting against the inner wall of said end plate and extending across the opening therein, a plurality of tubular members in parallel relationship with each other and the axis of said casing contained within the end portion of said casing and secured thereto, a sheet of wire mesh

15 within said casing abutting the inner ends of said tubular portions, and a mass of metallic wool filling the casing between said sheets of wire mesh to muffle sounds from exhaust gases passing through said muffler.

20 3. A muffler of the character described comprising a tubular casing, an end plate closing one end of said casing and having an axial opening therein with a surrounding tubular portion extending therefrom, a plurality of tubular mem-

30 bers extending inwardly from the opposite end of said casing parallel to the axis of said casing, a screen member contained within the casing and abutting the said inner ends of the tubular members, and a similar screen abutting the inner wall

35 of the end plate and extending across the opening therein, the said tubular members being secured together and to said casing to prevent displacement thereof, and a mass of fibers filling the space between the said wire mesh members to muffle the sound of exhaust gases passing through said casing.
